PIEZO ELECTRIC APPARATUS

Filed May 1, 1928

Inventor:
Augustus B. Tripp,
by *Charles E. Tullar*
His Attorney.

UNITED STATES PATENT OFFICE

AUGUSTUS B. TRIPP, OF CLIFTONDALE, MASSACHUSETTS, ASSIGNOR TO GENERAL ELECTRIC COMPANY, A CORPORATION OF NEW YORK

PIEZO-ELECTRIC APPARATUS

Application filed May 1, 1928. Serial No. 274,347.

My invention relates to piezo-electric apparatus, and has for its principal object the provision of an improved piezo-electric cell which is so constructed as to permit ready assembly and accurate adjustment of its various parts.

It is well-known that a piezo-electric element, such as a crystal of quartz or the like, will oscillate at a frequency dependent on its mechanical dimensions when it is subjected to an electrostatic field and that this characteristic of the piezo-electric element may be utilized to predetermine very accurately the frequency at which current is supplied from a source to an output circuit. It is desirable that the electrodes through which the electro-static field is applied to the active surfaces of the element be capable of accurate adjustment with respect to one another.

In making this adjustment, the element may be subjected to a compressive force applied through the electrodes or may rest upon one of the electrodes and be slightly spaced from the other. The latter arrangement has the advantage that oscillation of the element is readily initiated but has the disadvantage that the output is not so constant as it is when the element is subjected to slight pressure. In accordance with my invention, variation in the output is avoided by the provision of an improved cell including a resilient mechanical coupling which permits very accurate adjustment in the pressure applied to the active surfaces of the piezo-electric element.

My invention will be better understood from the following description when considered in connection with the accompanying drawing and its scope will be pointed out in the appended claims.

The drawing illustrates a piezo-electric apparatus constructed in accordance with my invention.

This apparatus includes a piezo-electric element 1 which is interposed between an adjustable electrode 2 and a floating electrode 3. This element is surrounded at its outer edges by an insulation collar 4, and is protected from variations in temperature by an insulation cover 5 mounted on an insula-

tion base 6. Potential is applied to the adjustable electrode 2 through a terminal 8 and a threaded support 9 and to the floating electrode 3 through a terminal 7, a threaded pedestal 10, an adjusting member 11 threaded into the pedestal 10 and a bolt 12 or a spiral spring 13 which surrounds the bolt 12 and is interposed between the adjusting member 11 and the electrode 3.

With this construction, the adjustable mechanical coupling between the electrodes 2 and 3 includes the member 9, the base 6, the pedestal 10, the adjusting member 11, the bolt 12 and the spring 13. It should be noted that the floating electrode 3, the spring 13, the bolt 12 and the threaded plug or adjusting member 11 are arranged to form a unit assembly which may be adjusted readily to apply any desired pressure to the active surfaces of the element 1. The proper adjustment of the electrode 2 is preferably made by first screwing it down until the floating electrode 3 is clamped against the top of the pedestal 10 by pressure exerted through the element 1 and then unscrewing the electrode 2 slightly so as to free the floating electrode 3 and leave it pressed against the element 1 by a pressure dependent on the adjustment of the unit assembly formed by the members 3, 11, 12 and 13. The maintenance of the electrodes in contact with the active surfaces of the piezo-electric element has the advantage that change in output due to temperature variations is largely avoided. This advantage is most marked in the case of very thin elements.

The floating electrode 3 and the element 1 are prevented from lateral displacement by the insulation barrier 4 which closely fits the upper periphery of the pedestal 10 and keeps the element 1 between the electrodes 2 and 3. It has been found that a piezo-electric cell of this construction can be roughly treated without damage and can be satisfactorily used in any desired position.

What I claim as new and desire to secure by Letters Patent of the United States, is:

1. In a piezo-electric apparatus, a unit assembly including a floating electrode, an adjusting member, a member fixed to said

floating electrode and extending through said adjusting member, and a spiral spring interposed between said adjusting member and said floating electrode.

- 5 2. In a piezo-electric apparatus, a unit assembly including a floating electrode, an adjusting member, a pin fixed to said electrode and extending through said adjusting member, and a spiral spring surrounding said pin
- 10 and extending between said floating electrode and said adjusting member.
- 15 3. In a piezo electric apparatus, the combination of a unit assembly including a floating electrode, an adjustable electrode spaced from said floating electrode for forming a crystal chamber, a spring arranged to support said floating electrode and means comprising a pair of threaded members for adjusting the position of said spring.
- 20 4. In a piezo electric apparatus, the combination of an adjustable electrode, a floating electrode spaced from said adjustable electrode for forming a crystal chamber, an adjusting member, and a spiral spring inter-
- 25 posed between said floating electrode and said adjusting member.

In witness whereof, I have hereunto set my hand this 28th day of April, 1928.

AUGUSTUS B. TRIPP.
